UNITED STATES PATENT OFFICE.

ANTON OHNEMUS, OF QUINCY, ILLINOIS, ASSIGNOR TO EXCELSIOR STOVE AND MANUFACTURING COMPANY, OF QUINCY, ILLINOIS.

FIRE-POT FOR STOVES AND FURNACES.

1,181,793.

Specification of Letters Patent. Patented May 2, 1916.

Application filed June 21, 1915. Serial No. 35,252.

To all whom it may concern:

Be it known that I, ANTON OHNEMUS, a citizen of the United States, and a resident of Quincy, in the county of Adams and 5 State of Illinois, have invented a certain new and useful Improvement in Fire-Pots for Stoves and Furnaces, of which the following is a specification.

My present invention relates generally to 10 improvements in stoves and furnaces, and more particularly to an improved fire pot therefor, my object being to provide a fire pot in the use of which the hydrocarbons escaping from fresh fuel will be better consumed within a stove or furnace, and the 15 waste of heat units so often amounting to a considerable percentage of the total heat efficiency of the fuels, may be reduced to a minimum. In order to accomplish this I 20 propose generally the construction of a fire pot in upper and lower sections, the lower section of which has vertical air channels communicating at their lower ends with and forming flues in which the air in its passage therethrough, is pre-heated, the upper 25 section of the fire pot having channels communicating with the channels of the lower section and also extending vertically, these channels of the upper section further communicating with vertical slots extending 30 from the top to the bottom of the upper section and through which the pre-heated air finds its way into the upper portion only of the firepot, thus more effectively combining with the hydrocarbons driven off 35 of the fresh fuel by the heat of the fire, and enabling a thorough consumption of the heat units ordinarily wasted by the escape of these hydro-carbons.

40 In the accompanying drawing wherein my invention is shown in detail, and which forms a part of this specification, Figure 1 is a vertical section through one side of a fire pot constructed in accordance with my invention. Fig. 2 is a horizontal view of the upper section of the firepot, being partly in top plan and partly in section. Fig. 3 is a top plan view of a portion of the lower section. Fig. 4 is a detail sectional perspective of a portion of the upper section of the firepot, and Fig. 5 is a similar view of a portion of the lower section.

Referring now to these figures, the upper and lower sections of my improved fire pot, 55 the relation between which in operative po-

sition is best seen in Fig. 1, are indicated therein at A and B respectively.

As best seen by reference to Figs. 1 and 3, the lower section B of the firepot has a plurality of vertical channels B', the sides of which are entirely inclosed, which form flues upwardly through which the air may find its way from the ash pit upon the wall C of which the lower section B is seated, a section of the grate D appearing in Fig. 60 1 in order to plainly establish the relationship between the upper and lower sections of the firepot and the adjacent portions of the stove or furnace as the case may be. The upper edge of the lower section B has a surrounding groove B² extending in a tortuous manner around the upper extended rings b' of the several vertical channels B', so as to enable the upper ends of these channels to fit closely against the lower edge of the 65 upper section A, the surrounding flange A' of which extends into the channel B² as plainly seen in Fig. 1, thus providing for the reception of suitable binding material 70 as shown at C in Fig. 1 joining the upper 75 and lower sections just mentioned.

By referring now to the upper section A it will be seen that in addition to its flange A' best seen in Fig. 4, it is provided with spacing lugs a' which engage the inner side 85 of the groove B² in which the flange A' seats, so as to properly position the upper and lower sections with respect to one another so as to bring the upper ends of the channels B' into perfect registry with the 90 lower ends of the vertical channels A² of the upper section, which latter channels extend vertically within the said section, being similar in number to those of the lower section, although closed at their upper ends and 95 provided with vertical slots A³ extending through the inner wall of the upper section A from its lower to its upper edge and thus for practically its entire width, to permit of the passage of the air pre-heated during 100 its movement through the several channels B' to find its way into the upper portion only of the firepot.

A construction as thus described is well adapted to carry out the objects beforementioned is simple and inexpensive, and has been found to be highly effective for the purpose intended.

I claim:

A firepot the wall of which is formed in 110

upper and lower sections, the lower section of which is provided with spaced vertical air channels surrounded by solid portions of said section and forming flues for the passage and pre-heating of air, and the upper section of which is provided with similar vertical flues, closed at their upper ends and provided with side slots communicating with the interior of the upper portion of the firepot whereby to supply thereto the air pre-heated in its passage through the chan-

nels of the lower section, said upper section having an otherwise smooth regularly curved inner surface and said upper and lower sections having relatively engaging means whereby to secure their proper relative positioning and promote alinement of their said vertical channels. 15

ANTON OHNEMUS.
